(57) **CLAIM**

The ornamental design for a queuing/mixing headset, as shown and described.

DESCRIPTION

FIG. 1 is a top plan view of the first embodiment of the queuing/mixing headset of the present invention showing my new design;

FIG. 2 is a front elevational view thereof;

FIG. 3 is a bottom plan view thereof;

FIG. 4 is a rear elevational view thereof;

FIG. 5 is a left side elevational view thereof;

FIG. 6 is a right side elevational view thereof;

FIG. 7 is a top plan view of the second embodiment of the queuing/mixing headset of the present invention showing my new design;

FIG. 8 is a front elevational view thereof;

FIG. 9 is a bottom plan view thereof;

FIG. 10 is a rear elevational view thereof;

FIG. 11 is a left side elevational view thereof;

FIG. 12 is a right side elevational view thereof;

FIG. 13 is a top plan view of the third embodiment of the queuing/mixing headset of the present invention showing my new design;

FIG. 14 is a front elevational view thereof;

FIG. 15 is a bottom plan view thereof;

FIG. 16 is a rear elevational view thereof;

FIG. 17 is a left side elevational view thereof; and,

FIG. 18 is a right side elevational view thereof.
